US0D1040393S

(12) **United States Design Patent** (10) **Patent No.:** **US D1,040,393 S**
(45) **Date of Patent:** **** Aug. 27, 2024**

(54) **DECORATIVE LIGHT CLIP**

(71) Applicant: **Dongguan Meiting Electronic Technology Co., Ltd.**, Dongguan (CN)

(72) Inventor: **Chengwei Song**, Dongguan (CN)

(73) Assignee: **Dongguan Meiting Electronic Technology Co., Ltd.**, Dongguan (CN)

(**) Term: **15 Years**

(21) Appl. No.: **29/869,730**

(22) Filed: **Jan. 6, 2023**

(51) LOC (14) Cl. **26-05**

(52) U.S. Cl.

USPC **D26/138**; D8/395

(58) **Field of Classification Search**

USPC D26/25, 113, 118, 142, 60, 61, 63, 138; D8/394, 395

(57) **CLAIM**

The ornamental design for a decorative light clip, as shown and described.

DESCRIPTION

FIG. 1 is a front perspective view of a decorative light clip, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the decorative light clip, which form no part of the claimed design.

1 Claim, 8 Drawing Sheets
